UNITED STATES PATENT OFFICE.

THEODORE PHILLIPS, OF WHITING, IOWA, ASSIGNOR OF ONE-HALF TO
EUGENE EGLI, OF SAME PLACE.

WASHING-MACHINE.

SPECIFICATION forming part of Letters Patent No. 333,666, dated January 5, 1886.

Application filed April 13, 1885. Serial No. 162,066. (No model.)

To all whom it may concern:

Be it known that I, THEODORE PHILLIPS, a citizen of the United States of America, and a resident of Whiting, in the county of 5 Monona and State of Iowa, have invented a new and useful Improvement in Washing-Machines, of which the following is a specification.

My invention relates to that class of washing-machines that have concave wash-board surfaces, upon which clothing is placed and pressed and rubbed by means of an oscillating adjustable and removable convex rubber; and my object is to avoid the necessity of lifting or adjusting the rubber in putting clothing in a tub, or taking them out; and I accomplish this by forming and combining an open-bottomed rubbing device with a tub, as herein-after set forth, in such a manner that articles 15 to be washed can be dropped into the rubber to be beat and carried and turned therein, and also rubbed upon the concave wash-board surface in the tub, to be thoroughly cleansed while submerged in the water in the tub, and 20 then taken out of the machine without lifting or adjusting the rubber.

Figure 1 of the accompanying drawings is a perspective view of my rubbing device, and Fig. 2 a vertical and longitudinal section of 25 the complete machine.

A represents a box-form tub such as are in common use. It has fixed legs to support it in an elevated position, and a concave wash-board surface, B, composed of wooden slats 35 fixed to the sides of the tub in such a manner that they will not come in contact with the sheet-metal bottom of the tub.

CC are the wooden side pieces of my rubber, preferably made concave at their under edges. 40 They are rigidly connected by means of wooden cross-pieces D, fixed to their lower corners by means of mortises and tenons, or in any suitable way. These cross-pieces are preferably placed in an inclined position, as clearly shown 45 in Fig. 1.

ff are small wooden bars, preferably round, fixed above the cross-pieces D, to aid in keeping articles within the rubber, as required to

beat and turn them, and also rub them upon the wash-board surface B.

50

g g are wooden arms fixed to the centers of the side pieces, C, to extend vertically and at right angles therefrom.

h is a round wooden bar fixed to the top ends of the arms to connect them, and to serve 55 as a handle for operating the rubber when pivoted within a tub, as illustrated by Fig. 2.

In the practical use of my rubber thus constructed and applied I simply place hot soap-suds in the tub, and then place the articles to 60 be washed within the open-bottomed rubber, and take hold of the handle and vibrate it. The clothing will be thereby pushed back and forth and rubbed over the concave wash-board, and pressed and beaten and turned by the 65 cross pieces and bars in the ends of the rubber, which allow the water to pass, but restrict the articles from passing outside of the rubber.

I am aware that a reciprocating rubber has been composed of solid sides and a series of 70 cross-pieces, and suspended in a tub in a manner similar to mine; but in no instance has a rubber been formed with an open bottom through which articles of clothing could be placed upon the wash-board underneath, 75 rubbed and pressed by the action of the rubber, and then removed from the machine without lifting the rubber, as contemplated by my invention.

I claim as my invention—

80

1. An open-bottomed rubbing device for washing-machines, composed of parallel sides C, ends D, cross-bars f, and arms g, substantially as and for the purposes set forth.

2. The combination of a rubbing device 85 having solid sides, connected at their ends by means of cross-pieces, an open bottom, and rigid arms extending vertically from the centers of the sides, in combination with a washing-machine tub having a concave wash-board 90 surface, to operate in the manner set forth, for the purposes specified.

THEODORE PHILLIPS.
